UNITED STATES PATENT OFFICE

WALTER V. WHATLEY, OF AKRON, OHIO

MACHINE-GUN TOY

Application filed February 19, 1930. Serial No. 429,635.

The present invention relates to a toy and has for its prime object to provide an apparatus from which a plurality of projectiles may be shot in quick succession in simulation of a machine gun.

Another very important object of the invention resides in the provision of a toy of this nature which is exceedingly simple in its construction, easy to manipulate, not likely to easily become out of order, strong and durable, thoroughly efficient and reliable in use and operation, and otherwise well adapted to the purpose for which it is designed.

With the above and numerous other objects in view as will appear as the description proceeds, the invention resides in certain novel features of construction, and in the combination and arrangements of parts as will be hereinafter more fully described and claimed.

In the drawing:

Figure 1 is a top plan view of a toy apparatus embodying the features of my invention,

Figure 2 is a vertical longitudinal section therethrough taken substantially on the line 2-2 of Figure 1,

Figure 3 is a similar view showing the plunger retracted,

Figure 4 is a perspective view of the plunger,

Figure 5 is a detail sectional view showing a hopper construction, and

Figure 6 is a sectional view taken substantially on the line 6-6 of Figure 2.

Figure 7 is a vertical cross section taken substantially on the line 7-7 of Figure 3.

Figure 8 is a vertical sectional view taken substantially on the line 8-8 Figure 3.

Referring to the drawing in detail it will be seen that the numeral 5 denotes a tripod on which is mounted a U-shaped bracket 6 the bottom cross bar of which is provided with a depending pin 7 rockable in the tripod 5 and held in place by nut 8.

An elongated tube 9 has an elongated opening in the top of the rear portion as is indicated at 10 and said rear portion is rockably mounted between the lower portions of the

trunnions 11 projecting into openings in said sides of the bracket. A shaft 12 is journalled through the upper ends of the sides of the bracket 6 and at one end terminates in an operating crank 14.

A hub 15 is fixed to the shaft 12 between the sides of the bracket 6 and has a plurality of radiating bolts 16 extending therefrom to move through the opening 10 when the crank 14 is rotated. A tube 17 rises from the tube adjacent the forward end thereof and if desired may have a telescope extension 18 or as is shown in Figure 3 or may terminate in a hopper 19 as is shown in Figure 5.

This tube 17 is supplied with a plurality of spherical projectiles 20. A flap 21 is provided in the tube 9 forwardly of the junction of the tube 17 therewith to normally extend downwardly across the upper portion of the tube 9 as is shown in Figure 3 for preventing a projectile from rolling forwardly.

A plunger 22 is slidable in the tube 9 and has a notch 23 in the upper portion of the striking end to accommodate the flap 21 when the plunger is disposed forwardly in the position shown in Figure 2. A bar 24 projects rearwardly from the plunger through a collar 25 in the tube 5 at the forward end of the opening 10 and the rear end of this bar terminates in the opening 10 with a rising projection 27 with which the spokes 16 are engageable.

A spring 28 disposed about the bar 24 impinging against the collar 25 and against the plunger 22 and normally urging the plunger 22 forwardly. Now when the crank 14 is rotated a spoke 16 will engage the upper beveled end of the extension 27 as is shown in Figure 2 and further rotation of the crank will cause the movement of the plunger 22 from the position shown in Figure 2 to the position shown in Figure 3 at which time a projectile 20 will drop down into the tube 5 and be held in place by the flap 21 and then a little further rotation of the crank will release said bolt from the extension 27 so that the springs 28 will move the plunger 22 forwardly to strike the projectile and seat the same out of the tube 9,

Obviously this tube 9 may be aimed because it may be rocked in the bracket 6 and because the bracket 6 may be rocked on the tripod. In order to aim the toy gun I provide a handle 30 having a reduced extension 31 fixed inside the rear end of the tube 9.

It is thought that the construction, operation, utility and advantages of this invention will now be quite apparent to those skilled in this art without a detail description thereof.

The present embodiment of the invention has been disclosed in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

A machine gun toy of the type described comprising a tripod consisting of a flat circular plate with a central hole, lugs projecting downwardly and outwardly from the underside of the plate at the edge thereof, a U-shaped bracket having its bight portion provided with a central dependent bolt for pivotingly mounting the bracket, and a washer and nut on the lower end of the bolt; a gun barrel comprising an elongated tube having a long slot in its upper side near its rear end, a cylindrical handle having a reduced cylindrical portion for engagement in the rear end of the barrel, and a tubular magazine rising perpendicularly from the upper side of the barrel near the front end thereof and communicating therewith, a shaft journaled across the upper end of the legs of the U-shaped bracket, and having a crank handle at one end thereof, a hub on the shaft within the said legs, and spokes projecting from said hub and adapted to pass into said slot upon rotation of the shaft, and a plunger in the forward portion of the barrel comprising a piston conformably made for close sliding fitting in the barrel and having a flattened portion on the upper forward portion thereof, a rod projected from the rear end of the piston and having an upwardly projected finger on its rear end having a forwardly facing angular contact surface on its upper end, and a collar fixed within the barrel at the forward end of the slot and slidably receiving said rod, and a helical spring about said rod and expanding against the rear end of the piston and the forward face of the collar, said contact surface of the finger adapted to be contacted by said spokes as the crank han-

dle is turned for intermittently retracting and releasing said plunger for expelling one at a time from the front end of the barrel a plurality of spherical projectiles fed into the barrel from said magazine and positioned by a flap depending into the barrel, said flattened portion of the piston adapted to accommodate the flap at the extreme forward position thereof.

In testimony whereof I affix my signature.

WALTER V. WHATLEY.
